United States Patent

Des. 242,078

Patented Oct. 26, 1976

242,078

RADIO

Howard S. Teller, Jr., Mundelein, Ill., assignor to Chicago
Display Company, Melrose Park, Ill.

Filed Feb. 12, 1975, Ser. No. 549,290

Term of patent 14 years

Int. Cl. D14—03
U.S. Cl. D56—4 B

FIG. 1

FIG. 2

FIG. 3

FIG. 4

FIG. 5

FIG. 1 is a top plan view of a radio, showing my new design;

FIG. 2 is a front elevation view thereof;

FIG. 3 is a bottom plan view thereof;

FIG. 4 is a right side elevational view thereof;

FIG. 5 is a rear elevation view thereof with the antenna in its upright position; and

FIG. 6 is a left side elevational view thereof.

I claim:

The ornamental design for a radio, substantially as shown and described.

FIG. 6
